(57) **CLAIM**

The ornamental design for a personal warming apparatus, as shown and described.

DESCRIPTION

FIG. 1 is a front view of a personal warming apparatus showing our new design;

FIG. 2 is a rear view thereof, having a release layer;

FIG. 3 is a top view thereof;

FIG. 4 is a bottom view thereof;

FIG. 5 is a right side view thereof;

FIG. 6 is a left side view thereof; and,

FIG. 7 is a rear view thereof, showing the release layer of FIG. 2 removed.

The relatively light shade lines on the surface portions indicate contour and not surface decoration.

The short dashed lines in FIGS. 1 and 7 and the dotted lines in FIGS. 3-6 are for the purpose of illustrating portions of the apparatus and form no part of the claimed design. The long dashed lines in FIG. 2 and corresponding lines in FIGS. 3 and 4 represent perforations and form no part of the claimed design.
